UNITED STATES PATENT OFFICE.

FRANK B. HALL, OF BERWYN, ILLINOIS, ASSIGNOR TO THE NATIONAL MALLEABLE CASTINGS COMPANY, OF CLEVELAND, OHIO, A CORPORATION OF OHIO.

SPOOL-WASHER.

1,148,491.

Specification of Letters Patent. Patented July 27, 1915.

Application filed September 22, 1914. Serial No. 862,896.

To all whom it may concern:

Be it known that I, FRANK B. HALL, a citizen of the United States, residing at Berwyn, Cook county, Illinois have invented a new and Improved Spool-Washer, of which the following is a specification, reference being had to the accompanying drawings, in which—

Figure 1 is a plan of one of the halves or parts of my improved washer; Fig. 2 is an elevation thereof; Fig. 3 is a section on lines III—III of Fig. 1 showing the two parts assembled; Fig. 4 is a section on lines IV—IV of Fig. 1 showing the two parts secured together, and Fig. 5 is a perspective of one of the parts.

My invention relates to washers of the spool type and consists in making the washer of two complementary and similar parts, thereby eliminating the necessity of the use of lateral cores in the process of manufacture, which results in greater accuracy in casting and in decreasing the cost of manufacture.

My invention also consists in the construction and coöperation of the parts which I shall hereinafter describe and claim.

Referring to the drawings, my improved washer consists in two complementary parts 30 of similar design, and hence I have designated the various parts with similar reference numerals. Each part has a base 2 which may be either the top or bottom of the washer, having a collar 3 about the bolt-hole 4. Extending radially from the collar 3 are the ribs 5, 6, 7, 8 and 9. The collar 3 and the ribs 5, 6, 8 and 9 are of the same height and, with the base 2, constitute one half the thickness of the completed washer. The rib 7 is twice the height of the other ribs and has upon its upper face a lug or boss 10. Diametrically opposite the boss 10, and at the same distance from the bolt hole 4, is an aperture 11 of slightly 45 larger diameter than the boss 10, extending through the base plate 2.

To assemble the washer the two halves are placed together with their ribs 5, 6, 8 and 9 abutting, and with the rib 7 of one 50 part bearing against the inner face of the base 2 of the other part. As the boss 10 and aperture 11 are diametrically opposite each other on each part, the bosses 10 will fit into the apertures 11 on opposite parts and will

protrude slightly therethrough. With the 55 two parts firmly held in this position, the bosses 10 are hammered until they spread and rivet over into the apertures 11. The edges of the apertures on the outer sides of the parts are slightly beveled or rounded, 60 to give the bosses a firmer grip when they are upset. In Fig. 4 I have shown one of the bosses 10 merely entered in an aperture 11, and the other of the bosses upset and interlocked in the corresponding aperture 65 11. When the washer is thus assembled the semi-circular notches 12 and 13 in the ribs 8 and 9 of one part will overlie the corresponding notches 12 and 13 in the ribs 8 and 9 of the other part and will thereby 70 form circular openings through these ribs. These openings are intended to permit the insertion of a wire therethrough, so that the washer may be placed in the desired position and be held there by the wire until 75 the washer is secured by a bolt.

Washers constructed in accordance with my invention are particularly intended for use on bolts or tie-rods, either as spacer blocks between beams or in pockets or recesses where nuts cannot be conveniently applied. In the latter cases the use of a washer embodying my invention enables the nut to be applied in a position in which it is possible to operate upon it with a 80 85 wrench.

It is obvious that various modifications may be made in the construction which I have shown and described herein.

What I claim is:

1. A washer consisting of two complementary parts, each part comprising a base, and a plurality of radially-disposed ribs upon said base, one of said ribs having a boss thereon adapted to interfit and be riveted into an aperture in the base of the other part.

2. A washer consisting of two complementary parts, each part comprising a base, a collar upon the inner face of the base, and radially-disposed ribs upon said base, one of said ribs having an extension thereon adapted to interfit and be riveted into an aperture on the other part.

3. A washer consisting of two complementary parts, each part comprising a base, and a plurality of radially-disposed ribs of the same height upon said base, adapted to bear

against corresponding ribs upon the other part, the said parts being secured together by a projection and slot engagement.

4. A washer consisting of two complementary parts, each part comprising a base, and a plurality of radially-disposed ribs of the same height and a rib of different height upon said base, the ribs of the same height being adapted to bear against corresponding ribs upon the other part, and the rib of different height carrying means for interlocking with the base of the other part.

5. A washer consisting of two complementary parts, each part comprising a base, 15 radially-disposed ribs upon said base, and a

plurality of said ribs having recesses therein adapted to coincide with complementary recesses in corresponding ribs on the other part, and the parts being secured together by a projection and slot engagement. 20

6. A washer comprising two interfitting parts, each part comprising a base, said parts having recess and projection engagements with each other bent to lock said parts permanently together.

FRANK B. HALL.
